WINDOW CONTROL MECHANISM

John H. Roethel, Detroit, Mich., assignor to
 Marvel Equipment Corporation, Detroit, Mich.,
 a corporation of Michigan

Application November 4, 1948, Serial No. 58,225

3 Claims. (Cl. 287—3)

1

This invention relates to window regulator mechanism and particularly mechanism for controlling the operation of glass or transparent panels or the like of vehicles, especially automobile bodies, an object of the invention being to provide an improved mechanism which is compact, relatively simple in construction and economical to manufacture, eliminates considerable frictional resistance to the movement of the window panel, is capable of being easily assembled, and is adapted for use without material changes to various types of windows.

A further object of the invention is to provide improved means for slidably connecting the end of a swinging window regulator arm to the lower edge of a sliding window panel or to a mounting plate, the improved construction permitting not only easy installation of the regulator but also easier operation thereof due to the reduction in frictional resistance during operation of the window regulator.

Another object of the invention is to provide an improved connecting means for the end of a swinging regulator arm, such means including a member which is formed with a longitudinal channel having the back wall thereof provided with a longitudinal slot through which the transverse stud or pin on the end of the regulator arm freely projects, this stud carrying a bearing element or washer, preferably formed of plastic material, which has smooth bearing engagement with the upper and lower generally horizontal walls of the channel and also the front wall of the member, and the stud being held against withdrawal by means of a removable device attachable to the end of the stud after it has been inserted through the slot in the back wall of the channel.

Other objects of this invention will appear in the following description and appended claims, reference being had to the accompanying drawings forming a part of this specification wherein like reference characters designate corresponding parts in the several views.

Fig. 1 is an inner fragmentary side elevation, partly broken away and partly in section, of an automobile door embodying the present invention.

Fig. 2 is an enlarged fragmentary section taken substantially through lines 2—2 of Fig. 1 looking in the direction of the arrows.

Fig. 3 is an exploded view of the component parts of the structure shown in Fig. 2.

Fig. 4 is a view generally similar to Fig. 2 but illustrating a modification.

2

Fig. 5 is an exploded view of the component parts of the structure shown in Fig. 4.

Before explaining in detail the present invention it is to be understood that the invention is not limited in its application to the details of construction and arrangement of parts illustrated in the accompanying drawings, since the invention is capable of other embodiments and of being practiced or carried out in various ways. 5 Also it is to be understood that the phraseology or terminology employed herein is for the purpose of description and not of limitation.

Referring to the drawings wherein I have illustrated, by way of example, certain embodiments 15 of the present invention, there is shown at 10 a door of an automobile body comprising a door frame of any suitable construction formed with a main window opening which is adapted to be closed by means of a vertically slidable glass or other transparent panel 11. It will be understood that the present invention may be utilized 20 in connection with any of the windows of an automobile or other vehicle body.

The sliding panel 11 is mounted in conventional manner within the window opening with the side and top edges thereof embraced within the usual glass run channels around the margin of the window opening when the window panel is fully raised. Secured to the lower edge of the 25 panel 11 is a retainer channel 12 to which the window regulator is adapted to be attached. The panel 11 may be guided within the window well in any suitable manner. In the present instance, by way of example, depending guide devices 13 and 14 are carried by the glass retainer channel 12 at opposite ends thereof, these guide devices 30 cooperating with fixed upright guides 15 and 16 within the window well. Since the guiding means for guiding opposite ends of the window panel within the window well form no part of the present invention, a further description 35 thereof is not deemed necessary herein.

The window panel 11 may be raised and lowered by means of a suitable window regulator mechanism 45 mounted within the window well below the main window opening. Depending upon requirements such regulator mechanism may embody a window regulator of the single arm or double arm type. In the present instance, there 50 is shown a window regulator of the cross arm type comprising a pair of intersecting crossed arms 17 and 18 for shifting the window panel into and out of the window well. These arms are pivoted together at 19 at the locality of their crossing and the construction and arrangement

of the arms are such that they will pass by each other during operation.

The inner or lower end of the arm 18, which may be termed the balance arm, is provided with a connection including a transverse stud 20 riveted to the end of the arm and slidably within a guideway or guide slot 21 in a mounting plate 22. This connection of the arm 18 with the mounting plate 22 will later be described in connection with Figs. 2 to 5 inclusive. The inner end of the regulator arm 17, which may be termed the driving arm, is rigidly attached to a gear sector 23 journaled on a mounting plate 24 by a stud 25 which is adjustable within an arcuate slot 26 in the plate, the stud being held in fixed adjusted position by means of a nut and lock washer 27. The gear 23 is driven by means of a pinion (not shown) secured in the usual manner to a transverse handle shaft 28 which may be turned by means of a crank handle mounted at the inner side of the door. The mounting plates 22 and 24 are each stamped from a single metal blank and are formed with suitable screw bosses 29 and 30, respectively, by means of which the mounting plates may be secured by screws to the inner door panel 31. The weight of the window panel 11 and attached parts is counterbalanced by means of a spiral or clock type spring 32, the inner end of which is anchored to the stud 19 and the outer end of which is anchored to a pin 33 secured to the arm 17.

The swinging arm 18 is provided at its outer end with a connection including a transverse stud 34 adapted to travel within a longitudinal guideway or guide slot 35 formed in a bracket 36 secured to the bottom of the retainer channel 12. Similarly the swinging arm 17 is provided at its outer end with a connection including a transverse stud 37 adapted to travel within a longitudinal guide slot or guideway 38 formed in a bracket 39 secured to the bottom of the retainer channel 12.

In Figs. 2 to 5 inclusive the construction of the bracket 39 together with the connection of the window regulator arm 17 thereto is shown. It will be understood that the same construction is provided for the connection of the window regulator arm 18 to the bracket 36 and also for the connection of the inner end of the regulator arm 18 to the mounting plate 22. In other words, the connecting means of the regulator arms at points 20, 34 and 37 are preferably identical and correspond to the construction shown in Figs. 2 to 5 inclusive.

Referring to Figs. 2 to 5 inclusive, the bracket 39 is formed with a flange 39a along its upper edge spot welded to the bottom of the glass retainer channel 12. The bracket is pressed or rolled to provide a longitudinally extending channel 40 forming upper and lower parallel horizontal walls 40a and 40b. After the channel 40 has been formed a portion of the back wall is punched or blanked out so as to form the horizontally extending guide slot 38. A similar channel and slot construction is formed in the mounting plate 22 and also in the bracket 36. The stud 37 is riveted to the outer end of the regulator arm 17 and is provided with a cylindrical transverse shank 41 of uniform diameter. An annular groove 42 is cut or machined adjacent the outer end of the stud shank 41. Adapted to be mounted on the shank 41 of the stud is a bearing washer or element 43 which has a bore 44 through which the stud shank is slidably into the position shown in Fig. 2. The washer 43 is formed with an an-

nular outwardly projecting disk-like portion 45. Extending from one side of this disk-like portion is a cylindrical bearing portion 46 of a diameter to fit within the channel 40 in bearing engagement with the opposed bearing surfaces of the walls 40a and 40b. The width of the bearing portion 46 of the washer preferably corresponds substantially to the depth of the channel 40 so as to cause the disk portion 45 to engage the front wall of the bracket member 39 when the parts are assembled as shown in Fig. 2. Extending from the disk portion 45 at the side thereof opposite to the bearing portion 46 is a cylindrical spacer portion 47 adapted for the purpose of spacing the flange or disk like portion 45 from the outer end of the regulator arm when the parts are assembled.

When the regulator arm carrying the bearing washer 43 is assembled with the bracket 39, the stud shank 41 is inserted through the slot 38 thereby positioning the bearing portion 46 of the washer within the channel 40 so as to have bearing engagement with the walls 40a and 40b. The stud projects through the slot 38 a sufficient distance, as shown in Fig. 2, to permit a washer 48 to be positioned on the shank 41 inwardly of the locking groove or slot 42. The workman then by the use of a suitable tool forces a spring cotter pin 49 transversely over the stud so as to snap it into position within the annular groove or slot 42 thereby locking the washer 43 against removal and also locking the stud 37 against withdrawal from the channel 40. With the parts thus assembled as shown in Fig. 2 the bearing portion 46 of the bearing element 43 will be permitted to slide freely with a minimum of friction within the channel 40 against the surfaces of the walls 40a and 40b thereof. Since the shank 41 of the stud preferably has a diameter somewhat less than the height of the slot 38, the shank of the stud will travel longitudinally within the guide slot 38 free of engagement with the edges thereof. This construction, in which the shank of the stud does not ride against the edges of the slot 38, is preferred in order to achieve best results since by eliminating frictional engagement of the stud with the raw edges of the slot 38 a very smooth operation is attained with a minimum of frictional resistance.

The construction illustrated in Figs. 4 and 5 is identical to that shown in Figs. 2 and 3 with the exception that the spacer portion 47 on the bearing washer 43 is omitted and instead the bearing washer is spaced from the regulator arm by means of a shoulder portion 50 on the stud 37. In forming the stud in this case stock is used having the diameter of the shoulder portion 50 and is machined down to provide the cylindrical bearing shank 41 corresponding to the bearing shank 41 in the previous embodiment.

In order to reduce to a minimum frictional resistance to the longitudinal travel of the studs 30, 34 and 37 in their respective guide slots and also to reduce to a minimum any objectionable noise resulting from vibration which might otherwise occur sometimes on account of slight play between the parts occasioned by variations due to production tolerances, I prefer to form the washers 43 and 48 of relatively soft non-metallic material which will eliminate, or substantially so, objectionable chattering or noises where accurate fit of the parts is not obtained. I prefer to mold the washers 43 and 48 of a plastic material which will slide easily and smoothly against the surfaces of the bracket 39 with a minimum of friction.

tional resistance and which will be highly wear resistant so as to be extremely durable. Polyethylene or nylon plastic have been found to be highly satisfactory material for use in molding the washers 43 and 48. Other thermoplastic materials, such as ethylcellulose, may also be utilized. By the use of such plastic materials in the fabrication of the bearing washers 43 and 48 superior results are achieved since it has been found that the window panel may be raised and lowered by the window regulator with considerably less effort than heretofore. By thus reducing greatly the frictional resistance it is possible to achieve considerable economies in the regulator construction owing to the fact that a regulator of lighter weight may be utilized than would otherwise be necessary.

I claim:

1. Connecting means for an end of a swinging regulator arm having a transverse stud secured to the end of the arm comprising a unitary member having a front vertical wall formed with a longitudinal channel to provide vertically spaced upper and lower longitudinally extending generally horizontal bearing walls terminating at 25 their outer edges in a single upright back wall joining said edges together, said back wall being formed with a longitudinal slot receiving said stud, a bearing element mounted on said stud and having a cylindrical portion fitting between said bearing walls and a disk-like portion engaging the front wall of said member, said stud having a spacer portion for spacing said disk-like portion from the regulator arm, and said stud being free of substantial frictional engagement 35 with the edges of said slot.

2. Connecting means for an end of a swinging regulator arm having a transverse stud secured to the end of the arm, comprising a unitary member having a front vertical wall formed with a 40 longitudinal channel to provide vertically spaced upper and lower longitudinally extending generally horizontal bearing walls terminating at

their outer edges in a single upright back wall joining said edges together, said back wall being formed with a longitudinal slot adapted to receive said stud, a bearing element adapted to be mounted on said stud and having a cylindrical portion fitting between said bearing walls and a disk-like portion engageable with the front wall of said member, and means for spacing said disk-like portion from the regulator arm.

3. Connecting means for an end of a swinging regulator arm having a transverse stud secured to the end of the arm, comprising a unitary member having a front vertical wall formed with a longitudinal channel to provide vertically spaced upper and lower longitudinally extending generally horizontal bearing walls terminating at their outer edges in a single upright back wall joining said edges together, said back wall being formed with a longitudinal slot adapted to receive said stud, a bearing element adapted to be mounted on said stud and having a cylindrical portion fitting between said bearing walls and a disk-like portion engageable with the front wall of said member, said element also having a spacer portion for spacing said disk-like portion from the regulator arm, and said stud being free of substantial frictional engagement with the edges of the slot.
